UNITED STATES PATENT OFFICE.

LOUIS KOSSUTH JOHNSON, OF BROOKLYN, NEW YORK, ASSIGNOR TO
ALDEN TYPE MACHINE COMPANY, OF NEW YORK, N. Y.

COMPOSITOR'S TYPE-STICK.

SPECIFICATION forming part of Letters Patent No. 708,646, dated September 9, 1902.

Application filed March 18, 1901. Serial No. 51,586. (No model.)

To all whom it may concern:

Be it known that I, LOUIS KOSSUTH JOHNSON, a citizen of the United States, residing in the city of New York, borough of Brooklyn, county of Kings, and State of New York, have invented certain new and useful Improvements in Compositors' Type-Sticks, of which the following is a specification sufficient to enable others skilled in the art to 10 which the invention appertains to make and use the same.

My improvements relate to compositors' type-sticks, and are designed to facilitate the removal of the types from the stick to a galley or elsewhere.

The invention consists, primarily, in making the front wall or flange movable or removable, so that it may be withdrawn from in front of the type composition to allow the 20 same to be pushed bodily off the bottom plate without being lifted therefrom, as has heretofore been necessary, and, secondarily, in certain special features of construction hereinafter described and claimed more specifically.

In the accompanying drawings, Figure 1 is a top view of my improved stick; Fig. 2, a like view with the front plate removed; Fig. 3, a rear edge view of the stick; Fig. 4, a 30 sectional elevation upon plane of line 4, 4, Fig. 1; Fig. 5, a transverse section upon plane of line 5, 5, Fig. 1. Fig. 6 is a view of the removable front plate.

A represents the floor or plate of the stick, 35 formed at one end with the usual abutment a. The front flange B consists of a strip of metal or other suitable material supported adjustably upon the plate A. This is preferably accomplished by means of uprights a' 40 a'', which support the front edge of the plate A, as shown in the drawings, or any other mechanical expedient may be resorted to for holding the flange B in place.

The adjustable abutment C, which has heretofore been secured to the rear of the front plate of the stick, in this case is formed with an

overlapping clasp c, which straddles the upper edge of the movable flange B. The adjustable abutment C is held in place by a clamp c', being pivotally connected to the 50 rear end of the abutment C and extending down to the plate A. The elasticity of the metal of which the clamp c' is composed may be relied upon to create sufficient frictional contact with the under side of the plate A to 55 prevent the movement of the abutment; but I prefer to render the device positive by the use of a set-screw c'', as shown in Figs. 3 and 4.

In use when it is desired to transfer the types T from the stick to the floor of a galley 60 or other device the front flange B is withdrawn, so that the types may be slid off the front end of the plate. Heretofore it has been necessary to lift them out of the stick, and there has been much loss of time and 65 labor by reason of the "pieing" of the type.

What I claim as my invention, and desire to secure by Letters Patent, is—

1. In a compositor's type-stick, the combination of the type-plate A, and abutment a, 70 the adjustable abutment C, formed with means for holding it in position upon the plate A, and the movable front flange B, supported adjustably upon said plate, for the purpose set forth.

2. A compositor's type-stick formed with a movable front flange substantially in the manner and for the purpose set forth.

3. In a compositor's type-stick the combination with the plate A, and abutment a, and 80 with the movable front flange B, of the adjustable abutment C, formed with the clasp c, to straddle the upper edge of the front flange B, said abutment C, being also formed with means by which it may be held stationary upon the plate A, substantially in the manner and for the purpose set forth.

LOUIS KOSSUTH JOHNSON.
